(57) **ABSTRACT**

This invention relates to an isolated nucleic acid fragment encoding a SCLB^R protein. The invention also relates to the construction of a chimeric gene encoding all or a portion of the SCLB^R protein, in sense or antisense orientation, wherein expression of the chimeric gene results in production of altered levels of the SCLB^R protein in a transformed host cell.

No. 6,303,332 which claims the benefit of provisional application No. 60/064,492 filed Nov. 5, 1997.*

FIELD OF THE INVENTION

This invention is in the field of plant molecular biology. More specifically, this invention pertains to nucleic acid fragments encoding proteins involved in corn (*Zea mays*) resistance to Southern corn leaf blight disease, caused by the fungus *Helminthosporium maydis*.

BACKGROUND OF THE INVENTION

Southern or Maydis Leaf Blight is a serious disease of corn caused by *Helminthosporium maydis* Nisik. (*Cochliobolus heterostrophus* (Drechs)). While corn hybrids with normal cytoplasm are resistant to Race T of the pathogen, Race O shows no differential reaction between plants with different cytoplasms; however, sources of resistance are available (Shurtleff (1973) Compendium of Corn Diseases). Chlorotic lesion resistance to Race O was identified in an East African line of corn (Jeweus and Daniel-Kalio (1968) *Plant Dis Rep.* 53:134-136). The resistant plants inhibit fungal sporulation and are distinguished by the presence of small chlorotic lesions. Significantly, the resistance is recessive (Smith and Hooker (1973) *Crop Science* 13:330-331). It was reported that disease is controlled by two linked recessive genes.

It is well established that resistance to many diseases in plants is mediated by the interaction of plant genes referred to as "R" genes with corresponding Avr genes expressed by the pathogen (Hammond-Kosack, K. E. and Jones, J. D. G. (1997) *Ann Rev. Plant Physiol Plant Mol. Bio.* 48:1-39). This interaction leads to the activation of plant responses which in turn results in increased resistance to disease. This resistance is frequently mediated by the "hypersensitive response", a localized cell death phenomenon that occurs in the areas of plant tissue invaded by the pathogen. This Avr/R interaction is race-specific; i.e., particular alleles of the plant R gene respond only to specific races of the pathogen which express a corresponding Avr gene (Flor, H. (1971) *Ann. Rev. Phytopathol.* 9:275-296). Most of the R genes characterized to date are dominant; i.e., resistance is exhibited by plants carrying the appropriate R allele in either an heterozygous or homozygous state. Some R genes have been isolated by map-based cloning. Many homologs of R genes have also been identified by sequence similarity. Because of the rapid evolution of plant resistance to disease, homology of a CDNA or genomic DNA sequence to a known R gene from a different plant species does not allow one to predict the pathogen specificity of that particular R gene. No general methods for such prediction exist today.

Genes involved in resistance of plants to plant pathogens may be used to engineer disease resistance into plants normally sensitive to disease using several different approaches. Transgenic plants containing alleles of R genes

demonstrate resistance to corresponding races of the pathogen (Wang, G.-L. et al. (1996) *Mol. Plant-Microbe Interact.* 9(9):850-855). The resistance genes may also be engineered to respond to non-naive signals derived from the pathogen.

In addition, pathogen-derived Avr genes may be expressed in a controlled manner in plants to strengthen the response to a pathogen. Genes further downstream from the R genes in the signal transduction pathways that transmit signals to the disease response effector genes may be engineered to directly respond to pathogen infection, thereby shortening the response pathway.

The process of the hypersensitive response to a pathogen, and the signaling networks involved, are poorly understood. In no case have all of the genes involved in transmitting the signal from the pathogen to the site of the initiation of the hypersensitive response been identified.

In a few cases, the functioning of a disease resistance mechanism different from the Avr/R interaction described above results in a recessive, rather than dominant pattern of resistance. One such example is the *Mlo* gene of barley, which conveys resistance to *Erysiphe graminis* f. sp. *hordei*. The barley gene has been recently isolated by a positional cloning approach (Bueschges, R. et al. (1997) *Cell* 88:695-705). The dominant (sensitive) allele (*Mlo*) is thought to encode a protein involved in regulation of leaf cell death and in the onset of pathogen defense. The partial or complete inactivation of *Mlo* results in the priming of the disease-resistance response even in the absence of the pathogen, and leads to increased resistance to *E. graminis*.

The available scientific data concerning *Mlo*-mediated disease resistance in barley points towards another approach to controlling disease: priming the pathogen response pathway by diminishing the effectiveness of negative regulation of the hypersensitive response. Appropriately engineered plants may show increased pathogen resistance at the expense of expressing some pathogen response-related genes even in the absence of pathogen. Sense or antisense inhibition or targeted gene disruption of *Mlo* and *Mlo*-related genes may have such an effect. Resistance to other pathogens may also be increased using this approach.

Mlo-related cDNA clones and DNA segments of genomic DNA, and their homologs and derivatives, may also be used as molecular probes to track inheritance of corresponding loci in genetic crosses, and thus facilitate the plant breeding process. Moreover, these DNA sequences may also be used as probes to isolate, identify and genetically map *Mlo* and other closely related disease resistance genes.

SUMMARY OF THE INVENTION

The instant invention relates to isolated nucleic acid fragments encoding a corn homolog of the barley *Mlo* protein. Specifically, the instant invention relates to isolated nucleic acid fragments encoding plant proteins involved in the regulation of plant cell death response in corn which, surprisingly, is associated with resistance of corn to Southern corn leaf blight disease caused by the fungus *Helminthosporium maydis*. In addition, this invention relates to nucleic acid fragments that are complementary to nucleic acid fragments encoding a corn homolog of the barley *Mlo* protein. The corn homolog of the barley *Mlo* gene and corresponding protein will hereinafter be referred to as the putative Southern corn leaf blight Resistance of SCLB^R gene or protein, respectively.

An additional embodiment of the instant invention pertains to a polypeptide encoding all or a substantial portion of a SCLB^R protein.

In another embodiment, the instant invention relates to a chimeric gene that comprises a nucleic acid fragment encoding the SCLB^R protein or to a chimeric gene that comprises a nucleic acid fragment that is complementary to the nucleic acid fragment encoding the SCLB^R protein, operably linked to suitable regulatory sequences, wherein expression of the chimeric gene results in production of levels of a SCLB^R protein in transformed host cells that are altered (i.e., increased or decreased) from the levels produced in untransformed host cells.

In a further embodiment, the instant invention concerns a transformed host cell comprising in its genome a chimeric gene encoding a SCLB^R, operably linked to suitable regulatory sequences. Expression of the chimeric gene results in production of altered levels of the encoded protein in the transformed host cell. The transformed host cell can be of eukaryotic or prokaryotic origin, and include cells derived from higher plants and microorganisms. The invention also includes transformed plants that arise from transformed host cells of higher plants, and seeds derived from such transformed plants.

An additional embodiment of the instant invention concerns a method of altering the level of expression of a SCLB^R protein in a transformed host cell comprising: a) transforming a host cell with a chimeric gene comprising a nucleic acid fragment encoding a SCLB^R protein; and b) growing the transformed host cell under conditions that are suitable for expression of the chimeric gene wherein expression of the chimeric gene results in production of altered levels of SCLB^R protein in the transformed host cell.

An addition embodiment of the instant invention concerns a method for obtaining a nucleic acid fragment encoding all or a substantial portion of an amino acid sequence encoding a SCLB^R protein.

A further embodiment of the instant invention concerns a method for using the instant nucleic acid fragments and their homologs and derivatives as molecular probes to monitor inheritance of corresponding loci in genetic crosses, and thus to facilitate and accelerate plant breeding. Additionally, the instant nucleic acid fragments may be used as probes to isolate, identify and genetically map SCLB^R and other closely related disease resistance genes.

BRIEF DESCRIPTION OF THE DRAWINGS AND SEQUENCE DESCRIPTIONS

The invention can be more fully understood from the following detailed description and the accompanying drawings and Sequence Listing which form a part of this application.

FIG. [1A and FIG. 1B] 1 is a genetic map of chromosome 6 of corn, including the position of cDNA clone cta1.pk0005.c1. The map was constructed using Mapmaker 3.0 for the Macintosh (Lander, E. S. et al. (1987) Genomics 1:174-181) and mapping data from Burr et al. (Burr et al. (1988) Genetics 118:519-526).

FIG. 2A and FIG. 2B is an alignment of nucleotides 781 to 1390 of the contig assembled with the nucleotide sequence of cDNA insert in clone cta1.pk0005.c1 and the 5' RACE product obtained using PCR primer P3 (SEQ ID NO:9) with the sequences of the 703 bp (SEQ ID NO:17) product obtained by PCR amplification of corn genomic DNA using primers P1 and P2. The intent of the intron sequences is indicated with an arrow. Intron sequences are shown in lowercase. The gt/ag invariant intron boundary sequences are bold and underlined.

FIG. 3A and FIG. 3B is an alignment of nucleotides 60 to 520 from the sequence of cDNA Mlo3b3 (SEQ ID NO:11)

with the sequence of the 765 bp (SEQ ID NO:18) product obtained by PCR amplification of corn genomic DNA using primers P1 and P2. The extent of the intron sequences is indicated with an arrow. Intron sequences are shown in lowercase. The gt/ag invariant intron boundary sequences are bold and underlined.

The following sequence descriptions and Sequence Listing attached hereto comply with the rules governing nucleotide and/or amino acid sequence disclosures in patent applications as set forth in 37 C.F.R. §1.821-1.825.

SEQ ID NO:1 is the nucleotide sequence comprising the entire cDNA insert in clone cc3. pk0007. g3 encoding an almost full-length SCLB^R protein.

SEQ ID NO:2 is the deduced amino acid sequence of an almost full-length SCLB^R protein derived from the nucleotide sequence of SEQ ID NO:1.

SEQ ID NO:3 is the nucleotide sequence comprising a portion of the cDNA insert in clone cr1n.pk0154.a3 encoding the C-terminal half of a SCLB^R protein.

SEQ ID NO:4 is the deduced amino acid sequence of the C-terminal half of a SCLB^R protein derived from the nucleotide sequence of SEQ ID NO:3.

SEQ ID NO:5 is the nucleotide sequence comprising a portion of the cDNA insert in clone cs1.pk0071.e3 encoding the C-terminus of a SCLB^R protein.

SEQ ID NO:6 is the deduced amino acid sequence of the C-terminus of a SCLB^R protein derived from the nucleotide sequence of SEQ ID NO:5.

SEQ ID NO:7 is the nucleotide sequence comprising the entire cDNA insert in clone cco1.pk0052.b10 encoding a full-length SCLB^R protein.

SEQ ID NO:8 is the deduced amino acid sequence of a full-length SCLB^R protein derived from the nucleotide sequence of SEQ ID NO:7.

SEQ ID NO:9 is the nucleotide sequence comprising a contig assembled from the entire cDNA insert in clone cta1.pk0005.c1 and the 5' RACE PCR product obtained using PCR primer P3 encoding a full-length SCLB^R protein.

SEQ ID NO:10 is the deduced amino acid sequence of a full-length SCLB^R protein derived from the nucleotide sequence of SEQ ID NO:9.

SEQ ID NO:11 is the nucleotide sequence comprising 45 Mlo3b3, the 3' RACE PCR product obtained using clone cta1.pk0005.c1 and PCR primer P1, encoding a fragment of a SCLB^R protein.

SEQ ID NO:12 is the deduced amino acid sequence of a 50 fragment of a SCLB^R protein derived from the nucleotide sequence of SEQ ID NO:11.

SEQ ID NO:13 is the nucleotide sequence comprising a portion of the cDNA insert in clone cen3n.pk0062.b7 encoding a fragment of a SCLB^R protein.

SEQ ID NO:14 is the deduced amino acid sequence of a 55 fragment of a SCLB^R protein derived from the nucleotide sequence of SEQ ID NO:13.

SEQ ID NO:15 is the nucleotide sequence of PCR primer P1.

SEQ ID NO:16 is the nucleotide sequence of PCR primer P2.

SEQ ID NO:17 is the nucleotide sequence of the 703 bp PCR product obtained by amplification of corn genomic DNA using PCR primers P1 and P2.

SEQ ID NO:18, is the nucleotide sequence of the 765 bp PCR product obtained by amplification of corn genomic DNA using PCR primers P1 and P2.

SEQ ID NO:19 is the nucleotide sequence of PCR primer P3.

SEQ ID NO:20 is the nucleotide sequence of PCR primer P4.

The Sequence Listing contains the one letter code for nucleotide sequence characters and the three letter codes for amino acids as defined in conformity with the IUPAC-UBMB standards described in Nucleic Acids Research 13:3021-3030 (1985) and in the Biochemical Journal 219 (No. 2):345-373 (1984) which are herein incorporated by reference. The symbols and format used for nucleotide and amino acid sequence data comply with the rules set forth in 37 C.F.R. §1.822.

DETAILED DESCRIPTION OF THE INVENTION

In the context of this disclosure, a number of terms shall be utilized. As used herein, an "isolated nucleic acid fragment" is a polymer of RNA or DNA that is single- or double-stranded, optionally containing synthetic, non-natural or altered nucleotide bases. An isolated nucleic acid fragment in the form of a polymer of DNA may be comprised of one or more segments of cDNA, genomic DNA or synthetic DNA. As used herein, "contig" refers to an assemblage of overlapping nucleic acid sequences to form one contiguous nucleotide sequence. For example, several DNA sequences can be compared and aligned to identify common or overlapping regions. The individual sequences can then be assembled into a single contiguous nucleotide sequence.

As used herein, "substantially similar" refers to nucleic acid fragments wherein changes in one or more nucleotide bases results in substitution of one or more amino acids, but do not affect the functional properties of the protein encoded by the DNA sequence. "Substantially similar" also refers to nucleic acid fragments wherein changes in one or more nucleotide bases does not affect the ability of the nucleic acid fragment to mediate alteration of gene expression by antisense or co-suppression technology. "Substantially similar" also refers to modifications of the nucleic acid fragments of the instant invention such as deletion or insertion of one or more nucleotides that do not substantially affect the functional properties of the resulting transcript vis-à-vis the ability to mediate alteration of gene expression by antisense or co-suppression technology or alteration of the functional properties of the resulting protein molecule. It is therefore understood that the invention encompasses more than the specific exemplary sequences.

For example, it is well known in the art that antisense suppression and co-suppression of gene expression may be accomplished using nucleic acid fragments representing less than the entire coding region of a gene, and by nucleic acid fragments that do not share 100% sequence identity with the gene to be suppressed. Moreover, alterations in a gene which result in the production of a chemically equivalent amino acid at a given site, but do not effect the functional properties of the encoded protein, are well known in the art. Thus, a codon for the amino acid alanine, a hydrophobic amino acid, may be substituted by a codon encoding another less hydrophobic residue, such as glycine, or a more hydrophobic residue, such as valine, leucine, or isoleucine. Similarly, changes, which result in substitution of one negatively charged residue for another, such as aspartic acid for glutamic acid, or one positively charged residue for another, such as lysine for arginine, can also be expected to produce a functionally equivalent product. Nucleotide changes which result in alteration of the N-terminal and C-terminal portions

of the protein molecule would also not be expected to alter the activity of the protein. Each of the proposed modifications is well within the routine skill in the art, as is determination of retention of biological activity of the encoded products. Moreover, the skilled artisan recognizes the substantially similar nucleic acid sequences encompassed by this invention are also defined by their ability to hybridize, under stringent conditions (0.1×SSC, 0.1% SDS, 65° C.), with the sequences exemplified herein. Preferred substantially similar nucleic acid fragments of the instant invention are those nucleic acid fragments whose DNA sequences are 80% identical to the coding sequence of the nucleic acid fragments reported herein. More preferred nucleic acid fragments are 90% identical to the coding sequence of the nucleic acid fragments reported herein. Most preferred are nucleic acid fragments that are 95% identical to the coding sequence of the nucleic acid fragments reported herein.

A "substantial portion" of an amino acid or nucleotide sequence comprises enough of the amino acid sequence of a polypeptide or the nucleotide sequence of a gene to afford putative identification of that polypeptide or gene, either by manual evaluation of the sequence by one skilled in the art, or by computer-automated sequence comparison and identification using algorithms such as BLAST (Basic Local Alignment Search Tool; Altschul, S. F., et al., (1993) J. Mol. Biol. 215:403-410 [; see also www.ncbi.nlm.nih.gov/BLAST/]). In general, a sequence of ten or more contiguous amino acids or thirty or more nucleotides is necessary in order to putatively identify a polypeptide or nucleic acid sequence as homologous to a known protein or gene. Moreover, with respect to nucleotide sequences, gene specific oligonucleotide probes comprising 20-30 contiguous nucleotides may be used in sequence-dependent methods of gene identification (e.g., Southern hybridization) and isolation (e.g., in situ hybridization of bacterial colonies or bacteriophage plaques). In addition, short oligonucleotides of 12-15 bases may be used as amplification primers in PCR in order to obtain a particular nucleic acid fragment comprising the primers. Accordingly, a "substantial portion" of a nucleotide sequence comprises enough of the sequence to afford specific identification and/or isolation of a nucleic acid fragment comprising the sequence. The instant specification teaches partial or complete amino acid and nucleotide sequences encoding one or more particular plant proteins. The skilled artisan, having the benefit of the sequences as reported herein, may now use all or a substantial portion of the disclosed sequences for purposes known to those skilled in this art. Accordingly, the instant invention comprises the complete sequences as reported in the accompanying Sequence Listing, as well as substantial portions of those sequences as defined above.

"Codon degeneracy" refers to divergence in the genetic code permitting variation of the nucleotide sequence without effecting the amino acid sequence of an encoded polypeptide. Accordingly, the instant invention relates to any nucleic acid fragment that encodes all or a substantial portion of the amino acid sequence encoding the SCLB^R protein as set forth in SEQ ID NOs:2, 4, 6, 8, 10, 12 and 14. The skilled artisan is well aware of the "codon-bias" exhibited by a specific host cell in usage of nucleotide codons to specify a given amino acid. Therefore, when synthesizing a gene for improved expression in a host cell, it is desirable to design the gene such that its frequency of codon usage approaches the frequency of preferred codon usage of the host cell.

"Synthetic genes" can be assembled from oligonucleotide building blocks that are chemically synthesized using pro-

cedures known to those skilled in the art. These building blocks are ligated and annealed to form gene segments which are then enzymatically assembled to construct the entire gene. "Chemically synthesized", as related to a sequence of DNA, means that the component nucleotides were assembled in vitro. Manual chemical synthesis of DNA may be accomplished using well established procedures, or automated chemical synthesis can be performed using one of a number of commercially available machines. Accordingly, the genes can be tailored for optimal gene expression based on optimization of nucleotide sequence to reflect the codon bias of the host cell. The skilled artisan appreciates the likelihood of successful gene expression if codon usage is biased towards those codons favored by the host. Determination of preferred codons can be based on a survey of genes derived from the host cell where sequence information is available.

"Gene" refers to a nucleic acid fragment that expresses a specific protein, including regulatory sequences preceding (5' non-coding sequences) and following (3' non-coding sequences) the coding sequence. "Native gene" refers to a gene as found in nature with its own regulatory sequences. "Chimeric gene" refers any gene that is not a native gene, comprising regulatory and coding sequences that are not found together in nature. Accordingly, a chimeric gene may comprise regulatory sequences and coding sequences that are derived from different sources, or regulatory sequences and coding sequences derived from the same source, but arranged in a manner different than that found in nature. "Endogenous gene" refers to a native gene in its natural location in the genome of an organism. A "foreign" gene refers to a gene not normally found in the host organism, but that is introduced into the host organism by gene transfer. Foreign genes can comprise native genes inserted into a non-native organism, or chimeric genes. A "transgene" is a gene that has been introduced into the genome by a transformation procedure.

"Coding sequence" refers to a DNA sequence that codes for a specific amino acid sequence. "Regulatory sequences" refer to nucleotide sequences located upstream (5' non-coding sequences), within, or downstream (3' non-coding sequences) of a coding sequence, and which influence the transcription, RNA processing or stability, or translation of the associated coding sequence. Regulatory sequences may include promoters, translation leader sequences, introns, and polyadenylation recognition sequences.

"Promoter" refers to a DNA sequence capable of controlling the expression of a coding sequence or functional RNA. In general, a coding sequence is located 3' to a promoter sequence. The promoter sequence consists of proximal and more distal upstream elements, the latter elements often referred to as enhancers. Accordingly, an "enhancer" is a DNA sequence which can stimulate promoter activity and may be an innate element of the promoter or a heterologous element inserted to enhance the level or tissue-specificity of a promoter. Promoters may be derived in their entirety from a native gene, or be composed of different elements derived from different promoters found in nature, or even comprise synthetic DNA segments. It is understood by those skilled in the art that different promoters may direct the expression of a gene in different tissues or cell types, or at different stages of development, or in response to different environmental conditions. Promoters which cause a gene to be expressed in most cell types at most times are commonly referred to as "constitutive promoters". New promoters of various types useful in plant cells are constantly being discovered; numerous examples may be found in the compilation by Okamuro

and Goldberg, (1989) *Biochemistry of Plants* 15:1-82. It is further recognized that since in most cases the exact boundaries of regulatory sequences have not been completely defined, DNA fragments of different lengths may have identical promoter activity.

The "translation leader sequence" refers to a DNA sequence located between the promoter sequence of a gene and the coding sequence. The translation leader sequence is present in the fully processed mRNA upstream of the translation start sequence. The translation leader sequence may affect processing of the primary transcript to mRNA, mRNA stability or translation efficiency. Examples of translation leader sequences have been described (Turner, R. and Foster, G. D. (1995) *Molecular Biotechnology* 3:225).

The "3' non-coding sequences" refer to DNA sequences located downstream of a coding sequence and include polyadenylation recognition sequences and other sequences encoding regulatory signals capable of affecting mRNA processing or gene expression. The polyadenylation signal is usually characterized by affecting the addition of polyadenylic acid tracts to the 3' end of the mRNA precursor. The use of different 3' non-coding sequences is exemplified by Ingelbrecht et al., (1989) *Plant Cell* 1:671-680.

"RNA transcript" refers to the product resulting from RNA polymerase-catalyzed transcription of a DNA sequence. When the RNA transcript is a perfect complementary copy of the DNA sequence, it is referred to as the primary transcript or it may be a RNA sequence derived from posttranscriptional processing of the primary transcript and is referred to as the mature RNA. "Messenger RNA (mRNA)" refers to the RNA that is without introns and that can be translated into protein by the cell. "cDNA" refers to a double-stranded DNA that is complementary to and derived from mRNA. "Sense" RNA refers to RNA transcript that includes the mRNA and so can be translated into protein by the cell. "Antisense RNA" refers to a RNA transcript that is complementary to all or part of a target primary transcript or mRNA and that blocks the expression of a target gene (U.S. Pat. No. 5,107,065, incorporated herein by reference). The complementarity of an antisense RNA may be with any part of the specific gene transcript, i.e., at the 5' non-coding sequence, 3' non-coding sequence, introns, or the coding sequence. "Functional RNA" refers to antisense RNA, ribozyme RNA, or other RNA that may not be translated but yet has an effect on cellular processes.

The term "operably linked" refers to the association of nucleic acid sequences on a single nucleic acid fragment so that the function of one is affected by the other. For example, a promoter is operably linked with a coding sequence when it is capable of affecting the expression of that coding sequence (i.e., that the coding sequence is under the transcriptional control of the promoter). Coding sequences can be operably linked to regulatory sequences in sense or antisense orientation.

The term "expression", as used herein, refers to the transcription and stable accumulation of sense (mRNA) or antisense RNA derived from the nucleic acid fragment of the invention. Expression may also refer to translation of mRNA into a polypeptide. "Antisense inhibition" refers to the production of antisense RNA transcripts capable of suppressing the expression of the target protein. "Overexpression" refers to the production of a gene product in transgenic organisms that exceeds levels of production in normal or non-transformed organisms. "Co-suppression" refers to the production of sense RNA transcripts capable of suppressing the expression of identical or substantially similar foreign or

endogenous genes (U.S. Pat. No. 5,23 1,020, incorporated herein by reference).

“Altered levels” refers to the production of gene product (s) in transgenic organisms in amounts or proportions that differ from that of normal or non-transformed organisms.

“Mature” protein refers to a post-translationally processed polypeptide; i.e., one from which any pre- or propeptides present in the primary translation product have been removed. “Precursor” protein refers to the primary product of translation of mRNA; i.e., with pre- and propeptides still present. Pre- and propeptides may be but are not limited to intracellular localization signals.

A “chloroplast transit peptide” is an amino acid sequence which is translated in conjunction with a protein and directs the protein to the chloroplast or other plastid types present in the cell in which the protein is made. “Chloroplast transit sequence” refers to a nucleotide sequence that encodes a chloroplast transit peptide. A “signal peptide” is an amino acid sequence which is translated in conjunction with a protein and directs the protein to the secretory system (Chrispeels, J. J., (1991) *Ann. Rev. Plant Phys. Plant Mol. Biol.* 42:21-53). If the protein is to be directed to a vacuole, a vacuolar targeting signal (supra) can further be added, or if to the endoplasmic reticulum, an endoplasmic reticulum retention signal (supra) may be added. If the protein is to be directed to the nucleus, any signal peptide present should be removed and instead a nuclear localization signal included (Raikhel (1992) *Plant Phys.* 100:1627-1632).

“Transformation” refers to the transfer of a nucleic acid fragment into the genome of a host organism, resulting in genetically stable inheritance. Host organisms containing the transformed nucleic acid fragments are referred to as “transgenic” organisms. Examples of methods of plant transformation include Agrobacterium-mediated transformation (De Blaere et al. (1987) *Meth. Enzymol.* 143:277) and particle-accelerated or “gene gun” transformation technology (Klein et al. (1987) *Nature (London)* 327:70-73; U.S. Pat. No. 4,945,050, incorporated herein by reference).

Standard recombinant DNA and molecular cloning techniques used herein are well known in the art and are described more fully in Sambrook, J., Fritsch, E. F. and Maniatis, T. *Molecular Cloning: A Laboratory Manual*; Cold Spring Harbor Laboratory Press: Cold Spring Harbor, 1989 (hereinafter “Maniatis”).

Nucleic acid fragments encoding at least a portion of several corn homologs of the barley Mlo protein have been isolated and identified by comparison of random plant cDNA sequences to public databases containing nucleotide and protein sequences using the BLAST algorithms well known to those skilled in the art. These nucleic acid fragments encode plant proteins involved in the regulation of plant cell death response in corn which, surprisingly, is associated with resistance of corn to southern corn leaf blight disease caused by the fungus *Helminthosporium maydis*. Table 1 lists the designation of the cDNA clones that comprise the nucleic acid fragments encoding SCLB^R proteins.

TABLE 1

Corn Homologs of Barley Mlo Protein

	cr1n.pk0154.a3	corn
	cs1.pk0071.e3	corn
	cta1.pk0005.c1	corn
	mlo3b3	corn

The homology with the barley Mlo protein indicated that these cDNAs corresponded to genes involved in disease resistance, but did not provide information as to the possible disease specificity in corn; *Erysiphe graminis*, the causative agent of powdery mildew in barley, is not a pathogen of corn. Ultimately, disease specificity information was provided by genetic mapping experiments.

PCR amplification of maize genomic DNA using two primers, P1 and P2, designed using the nucleic acid sequence of cDNA clone cta1.pk0005. c1. resulted in the amplification of two DNA segments, both homologous to cta1.pk0005.c1. but differing in the numbers of introns (see Example 4). Genetic mapping experiments (see Example 5) placed one of the two genomic segments on chromosome 6, in Bin 6.01, between markers BNL7.28 and UMC59. Three disease resistance loci map to the same bin on chromosome 6: Maize dwarf mosaic virus (MDMV), wheat streak mosaic virus (WSMV) and Southern corn leaf blight (SCLB). Of the three disease resistance loci, the SCLB locus is unique in that it is the only known recessive disease resistance locus in corn. Therefore, it is highly likely that the Mlo homolog represented by the 765 bp amplification product containing three introns corresponds to the Southern corn leaf blight resistance (SCLB^R) gene. The second genomic sequence, which contains two introns, is likely to be a second, linked SCLB^R gene. The existence of two linked genes has been reported by Craig and Fajemisin (Craig, J. and Fajemisin, J. M (1969) *Plant Dis. Rep.* 53:742-743).

The nucleic acid fragments of the instant invention may be used to isolate cDNAs and genes encoding homologous SCLB^R proteins from the same or other plant species. Isolation of homologous genes using sequence-dependent protocols is well known in the art. Examples of sequence-dependent protocols include, but are not limited to, methods of nucleic acid hybridization, and methods of DNA and RNA amplification as exemplified by various uses of nucleic acid amplification technologies (e.g., polymerase chain reaction, ligase chain reaction).

For example, genes encoding other SCLB^R proteins, either as cDNAs or genomic DNAs, could be isolated directly by using all or a portion of the instant nucleic acid fragments as DNA hybridization probes to screen libraries from any desired plant employing methodology well known to those skilled in the art. Specific oligonucleotide probes based upon the instant nucleic acid sequences can be designed and synthesized by methods known in the art (Maniatis). Moreover, the entire sequences can be used directly to synthesize DNA probes by methods known to the skilled artisan such as random primer DNA labeling, nick translation, or end-labeling techniques, or RNA probes using available in vitro transcription systems. In addition, specific primers can be designed and used to amplify a part or all of the instant sequences. The resulting amplification products can be labeled directly during amplification reactions or labeled after amplification reactions, and used as probes to

isolate full length cDNA or genomic fragments under conditions of appropriate stringency.

In addition, two short segments of the instant nucleic acid fragments may be used in polymerase chain reaction protocols to amplify longer nucleic acid fragments encoding homologous genes from DNA or RNA. The polymerase chain reaction may also be performed on a library of cloned nucleic acid fragments wherein the sequence of one primer is derived from the instant nucleic acid fragments, and the sequence of the other primer takes advantage of the presence of the polyadenylic acid tracts to the 3' end of the mRNA precursor encoding plant genes. Alternatively, the second primer sequence may be based upon sequences derived from the cloning vector. For example, the skilled artisan can follow the RACE protocol (Frohman et al., (1988) Proc. Natl. Acad. Sci. USA 85:8998) to generate cDNAs by using PCR to amplify copies of the region between a single point in the transcript and the 3' or 5' end. Primers oriented in the 3' and 5' directions can be designed from the instant sequences. Using commercially available 3' RACE or 5' RACE systems (BRL), specific 3' or 5' cDNA fragments can be isolated (Ohara et al., (1989) Proc. Natl. Acad. Sci. USA 86:5673; Loh et al., (1989) Science 243:217). Products generated by the 3' and 5' RACE procedures can be combined to generate full-length cDNAs (Froliman, M. A. and Martin, G. R., (1989) Techniques 1:165).

Availability of the instant nucleotide and deduced amino acid sequences facilitates immunological screening of cDNA expression libraries. Synthetic peptides representing portions of the instant amino acid sequences may be synthesized. These peptides can be used to immunize animals to produce polyclonal or monoclonal antibodies with specificity for peptides or proteins comprising the amino acid sequences. These antibodies can be then be used to screen cDNA expression libraries to isolate full-length cDNA clones of interest (Lemer, R. A. (1984) Adv. Immunol. 36:1; Maniatis).

The nucleic acid fragments of the instant invention may be used to create transgenic plants in which the disclosed SCLB^R proteins are present at higher or lower levels than normal or in cell types or developmental stages in which they are not normally found. This would have the effect of altering the level of SCLB^R in those cells, and thus changing the ability of corn to resist certain diseases.

Overexpression of the SCLB^R proteins of the instant invention may be accomplished by first constructing a chimeric gene in which the coding region is operably linked to a promoter capable of directing expression of a gene in the desired tissues at the desired stage of development. For reasons of convenience, the chimeric gene may comprise promoter sequences and translation leader sequences derived from the same genes. 3' Non-coding sequences encoding transcription termination signals may also be provided. The instant chimeric gene may also comprise one or more introns in order to facilitate gene expression.

Plasmid vectors comprising the instant chimeric gene can then be constructed. The choice of plasmid vector is dependent upon the method that will be used to transform host plants. The skilled artisan is well aware of the genetic elements that must be present on the plasmid vector in order to successfully transform, select and propagate host cells containing the chimeric gene. The skilled artisan will also recognize that different independent transformation events will result in different levels and patterns of expression (Jones et al., (1985) EMBO J.4:2411-2418; De Almeida et al., (1989) Mol. Gen. Genetics 218:78-86), and thus that multiple

events must be screened in order to obtain lines displaying the desired expression level and pattern. Such screening may be accomplished by Southern analysis of DNA, Northern analysis of mRNA expression, Western analysis of protein expression, or phenotypic analysis.

For some applications it may be useful to direct the instant SCLB^R gene product to different cellular compartments, or to facilitate its secretion from the cell. It is thus envisioned that the chimeric gene described above may be further supplemented by altering the coding sequence to encode SCLB^R proteins with appropriate intracellular targeting sequences such as transit sequences (Keegstra, K. (1989) Cell 56:247-253), signal sequences or sequences encoding endoplasmic reticulum localization (Cluispeels, J. J., (1991) Ann. Rev. Plant Phys. Plant Mol. Biol. 42:21-53), or nuclear localization signals (Raikhel, N. (1992) Plant Phys. 100:1627-1632) added and/or with targeting sequences that are already present removed. While the references cited give examples of each of these, the list is not exhaustive and more targeting signals of utility may be discovered in the future.

It may also be desirable to reduce or eliminate expression of genes encoding SCLB^R proteins in plants for some applications. In order to accomplish this, a chimeric gene designed for co-suppression of the instant SCLB^R protein can be constructed by linking a gene or gene fragment encoding an SCLB^R protein to plant promoter sequences. Alternatively, a chimeric gene designed to express antisense RNA for all or part of the instant nucleic acid fragment can be constructed by linking the gene or gene fragment in reverse orientation to plant promoter sequences. Either the co-suppression or antisense chimeric genes could be introduced into plants via transformation wherein expression of the corresponding endogenous genes are reduced or eliminated.

For example, the instant nucleic acid fragments may be combined in sense or antisense orientation with a suitable plant expression vector comprising a strong plant promoter sequence and plant terminator sequences. The recombinant vector may then be introduced into plants by transformation using techniques well known to those skilled in this art. Some of the transgenic plants recovered from the transformation process will exhibit diminished expression of the gene corresponding to the instant nucleic acid fragments. These plants may be identified by Northern blot analysis. These individuals may then be tested for disease resistance, and resistant individuals recovered for future use as a source of genetically controlled resistance in plant breeding schemes. Longer cDNA clones, especially ctal.pk0005.c1. cc3.pk0007.g3 and cco1.pk0052.b10 are preferred. cDNA clones cs1.pk0071.e3, cr1n.pk0154.a3, mlo3b3 and cen3n.pk0062.b7 may also be used in a similar way to inhibit expression of their corresponding genes.

The instant SCLB^R protein (or portions thereof) may be produced in heterologous host cells, particularly in the cells of microbial hosts, and can be used to prepare antibodies to the these proteins by methods well known to those skilled in the art. The antibodies are useful for detecting SCLB^R protein in situ in cells or in vitro in cell extracts. Preferred heterologous host cells for production of the instant SCLB^R protein are microbial hosts. Microbial expression systems and expression vectors containing regulatory sequences that direct high level expression of foreign proteins are well known to those skilled in the art. Any of these could be used to construct a chimeric gene for production of the instant SCLB^R protein. This chimeric gene could then be introduced into appropriate microorganisms via transformation to provide high level expression of the encoded SCLB^R protein.

An example of a vector for high level expression of the SCLB^R protein in a bacterial host is provided (Example 8).

All or a substantial portion of the nucleic acid fragments of the instant invention may also be used as probes for genetically and physically mapping the genes that they are a part of, and as markers for traits linked to those genes. Such information may be useful in plant breeding in order to develop lines with desired phenotypes. For example, the instant nucleic acid fragments may be used as restriction fragment length polymorphism (RFLP) markers. Southern blots (Maniatis) or restriction-digested plant genomic DNA may be probed with the nucleic acid fragments of the instant invention. The resulting banding patterns may then be subjected to genetic analyses using computer programs such as MapMaker (Lander et al., (1987) *Genomic*, 1:174–181) in order to construct a genetic map. In addition, the nucleic acid fragments of the instant invention may be used to probe Southern blots containing restriction endonuclease-treated genomic DNAs of a set of individuals representing parent and progeny of a defined genetic cross. Segregation of the DNA polymorphisms is noted and used to calculate the position of the instant nucleic acid sequence in the genetic map previously obtained using this population (Botstein, D. et al., (1980) *Am. J. Hum. Genet.* 32:314–331).

The production and use of plant gene-derived probes for use in genetic mapping is described in R. Bernatzky, R. and Tanksley, S. D. (1986) *Plant Mol. Biol. Reporter* 4(1):37–41. Numerous publications describe genetic mapping of specific cDNA clones using the methodology outlined above or variations thereof. For example, F2 intercross populations, backcross populations, randomly mated populations, near isogenic lines, and other sets of individuals may be used for mapping. Such methodologies are well known to those skilled in the art.

Nucleic acid probes derived from the instant nucleic acid sequences may also be used for physical mapping (i.e., placement of sequences on physical maps; see Hoheisel, J. D., et al., In: *Nonmammalian Genomic Analysis. A Practical Guide*, Academic press 1996, pp. 319–346, and references cited therein).

In another embodiment, nucleic acid probes derived from the instant nucleic acid sequences may be used in direct fluorescence in situ hybridization (FISH) mapping (Trask, B. J. (1991) *Trends Genet.* 7:149–154). Although current methods of FISH mapping favor use of large clones (several to several hundred KB; see Laan, M. et al. (1995) *Genome Research* 5:13–20), improvements in sensitivity may allow performance of FISH mapping using shorter probes.

A variety of nucleic acid amplification-based methods of genetic and physical mapping may be carried out using the instant nucleic acid sequences. Examples include allele-specific amplification (Kazazian, H. H. (1989) *J. Lab. Clin. Med.* 114(2):95–96), polymorphism of PCR-amplified fragments (CAPS; Sheffield, V. C. et al. (1993) *Genomics* 16:325–332), allele-specific ligation (Landegren, U. et al. (1988) *Science* 241:1077–1080), nucleotide extension reactions (Sokolov, B. P. (1990) *Nucleic Acid Res.* 18:3671), Radiation Hybrid Mapping (Walter, M. A. et al. (1997) *Nature Genetics* 7:22–28) and Happy Mapping (Dear, P. H. and Cook, P. R. (1989) *Nucleic Acid Res.* 17:6795–6807). For these methods, the sequence of a nucleic acid fragment is used to design and produce primer pairs for use in the amplification reaction or in primer extension reactions. The design of such primers is well known to those skilled in the art. In methods employing PCR-based genetic mapping, it may be necessary to identify DNA sequence differences

between the parents of the mapping cross in the region corresponding to the instant nucleic acid sequence. This, however, is generally not necessary for mapping methods.

For example, genetic diagnostics of the southern corn leaf blight (SCLB), maize dwarf mosaic virus (MDMV), wheat streak mosaic virus (WSMV) loci, and of other loci corresponding or tightly linked to cta1.pk0005.c1 and related cDNAs may be performed. Knowledge and availability of the nucleotide sequences corresponding to the corn *Mlo* homolog embodies by cDNA clone cta1.pk0005.c1 allows one skilled in the art to use one of many generally known techniques, like restriction fragment length polymorphism, allele specific PCR, single strand conformational polymorphism, allele-specific ligation. Cleaved Amplified Polymorphic Fragments (CAPS) and other similar methods discussed above and known to those skilled in the art, to follow the inheritance of a particular allele in genetic crosses during the process of plant breeding. Through this process, the plant carrying the alleles conferring disease resistance may be always recovered reliably.

For example, the 765 bp PCR fragment, which is produced only from the CM37 genotype and not from the T232 genotype using primers designed from the nucleotide sequence of cDNA clone cta1.pk0005.c1. is therefore polymorphic between these two genotypes and could be used to follow inheritance of the allele corresponding to the 765 bp PCR fragment in crosses of CM37 and T232, and in any crosses with a genotype which does not produce the 765 bp fragment in the above described PCR process.

Loss of function mutant phenotypes may be identified for the instant cDNA clones either by target gene disruption protocols or by identifying specific mutants for these genes contained in a maize population carrying mutation in all possible genes (Ballinger and Benzer, (1989) *Proc. Natl. Acad. Sci. USA* 86:9402; Koes et al., (1995) *Proc. Natl. Acad. Sci. USA* 92:8149; Bensen et al., (1995) *Plant Cell* 7:75). The latter approach may be accomplished in two ways. First, short segments of the instant nucleic acid fragments may be used in polymerase chain reaction protocols in conjunction with a mutation tag sequence primer on DNAs prepared from a population of plants in which Mutator transposons or some other mutation-causing DNA element has been introduced (see Bensen, slipra). The amplification of a specific DNA fragment with these primers indicates the insertion of the mutation tag element in or near the plant SCLB^R gene. Alternatively, the instant nucleic acid fragment may be used as a hybridization probe against PCR amplification products generated from the mutation population using the mutation tag sequence primer in conjunction with an arbitrary genomic site primer, such as that for a restriction enzyme site-anchored synthetic adaptor. With either method, a plant containing a mutation in the endogenous SCLB^R gene can be identified and obtained. This mutant plant can then be used to determine or confirm the natural function of the SCLB^R gene product.

EXAMPLES

The present invention is further defined in the following Examples, in which all parts and percentages are by weight and degrees are Celsius, unless otherwise stated. It should be understood that these Examples, while indicating preferred embodiments of the invention, are given by way of illustration only. From the above discussion and these Examples, one skilled in the art can ascertain the essential characteristics of this invention, and without departing from the spirit and scope thereof, can make various changes and modifications of the invention to adapt it to various usages and conditions.

Example 1

Composition of CDNA Libraries, Isolation and Sequencing of cDNA clones CDNA libraries representing mRNAs from various corn tissues were prepared. The characteristics of the libraries are described below.

TABLE 2

cDNA Libraries from Corn		
Library	Tissue	Clone
cc3	Corn Callus Embryo	cc3.pk0007.g3
cco1	Corn Cob of 67 Day Old Plants Grown in Green House	cco1.pk0052.b10
cen3n	Corn Endosperm 20 Days After Pollination*	cen3n.pk0062.b7
cr1n	Corn Root From 7 Day Old Seedlings*	cr1n.pk0154.a3
cs1	Corn Silk	cs1.pk0071.e3
cta1	Corn Tassel	cta1.pk0005.c1

*These libraries were normalized essentially as described in U.S. Pat. No. 5,482,845, incorporated herein by reference.

cDNA libraries were prepared in Uni-ZAP™ XR vectors according to the manufacturer's protocol (Stratagene Cloning Systems, La Jolla, Calif.). Conversion of the Uni-ZAP™ XR libraries into plasmid libraries was accomplished according to the protocol provided by Stratagene. Upon conversion, cDNA inserts were contained in the plasmid vector pBluescript, CDNA inserts from randomly picked bacterial colonies containing recombinant pBluescript plasmids were amplified via polymerase chain reaction using primers specific for vector sequences flanking the inserted cDNA sequences or plasmid DNA was prepared from cultured bacterial cells. Amplified insert DNAs or plasmid DNAs were sequenced in dye-primer sequencing reactions to generate partial cDNA sequences (expressed sequence tags of "ESTs"; see Adams, M. D. et al., (1991) *Science* 252:1651). The resulting ESTs were analyzed using a Perkin Elmer Model 377 fluorescent sequencer.

Example 2

Identification of cDNA Clones

ESTs encoding SCLB^R proteins were identified by conducting BLAST (Basic Local Alignment Search Tool; Altschul, S. F. et al., (1993) *J. Mol. Biol.* 215:403-410; see also www.ncbi.nlm.nih.gov/BLAST/) searches for similarity to sequences contained in the BLAST "nr" database (comprising all non-redundant GenBank CDS translations, sequences derived from the 3-dimensional structure Brookhaven Protein Data Bank, the last major release of the SWISS-PROT protein sequence database, EMBL, and DDBJ databases). The cDNA sequences obtained in Example 1 were analyzed for similarity to all publicly available DNA sequences contained in the "nr" database using the BLASTN° FN algorithm provided by the National Center for Biotechnology Information (NCBI). The DNA sequences were translated in all reading frames and compared for similarity to all publicly available protein sequences contained in the "nr" database using the BLASTX algorithm (Gish, W. and States, D. J. (1993) *Nature Genetics* 3:266-272) provided by the NCBI. For convenience, the P-value (probability) of conserving match of a cDNA sequence to a sequence contained in the searched databases merely by chance as calculated by BLAST are reported herein as "pLog" values, which represent the negative of the logarithm of the reported P-value. Accordingly, the greater the pLog value, the greater the likelihood that the cDNA sequence and the BLAST "hit" represent homologous proteins.

Example 3

Characterization of cDNA Clones Encoding SCLB^R Proteins

The BLASTX search using the nucleotide sequences from clones cen3n.pk0062.b7, cs1.pk0071.e3, cc3.pk0007.g3 and cta1.pk0005.c1 revealed similarity of the proteins encoded by the cDNAs to the barley mlo gene (NCBI gi Accession No. 1877221). The BLASTX results for each of these ESTs are shown in Table 3:

TABLE 3

BLASTX Results for Clones Encoding Polypeptides Homologous to Barley Mlo Protein	
Clone	BLAST pLog Score 1877221 (barley)
cen3n.pk0062.b7	73.04
cs1.pk0071.e3	9.30
cc3.pk0007.g3	15.77
cta1.pk0005.c1	53.89

Further BLASTX analyses were performed which revealed that these ESTs and sequences from other clones contained similarities to putative *Arabidopsis thaliana* Mlo homologs found in the NCBI database. BLASTX search using the nucleotide sequences from clones cc3.pk0007.g3, cr1n.pk0154.a3 and cs1.pk0071.e3 revealed similarity to the *Arabidopsis thaliana* AtMlo-h1 protein (NCBI gi Accession No. 2765817). BLASTX search using the nucleotide sequences from clone cco1.pk0052.b10 revealed similarity to the Barley Mlo protein isolog from *Arabidopsis thaliana* (NCBI gi Accession No. 2252632). The BLASTX searches using (i) the nucleotide sequences from the contig assembled of the entire cDNA sequence in clone cta1.pk0005.c1 and the 5' RACE product obtained using Marathon™ cDNA amplification kit (Clontech catalog No. K1802-1) with PCR primer P3 and (ii) using the nucleotide sequence from mlo3b3, and 3' RACE product from clone cta1.pk0005.c1 obtained using Marathon™ cDNA amplification kit (Clontech catalog No. K1802-1) with PCR primer P1, revealed similarity to the putative Mlo protein from *Arabidopsis thaliana* (NCBI gi Accession No. 2459447). These three *Arabidopsis thaliana* sequences have been identified as Mlo homologs based on sequence comparisons with the *Hordeum vulgare* Mlo sequence. The BLASTX search using the nucleotide sequences from the contig assembled with the sequence of the entire cDNA in clone cen3n.pk0062.b7 and the sequence of its 5' RACE product obtained using Marathon™ cDNA amplification kit (Clontech catalog No. K1802-1) with PCR primer P4 revealed a higher pLog value to the Mlo protein from *Hordeum vulgare* (NCBI gi Accession No. 1877221) than did the EST sequence. The BLAST results for each of these sequences are shown in Table 4:

TABLE 4

BLAST Results for Clones Encoding Polypeptides Homologous to Mlo Proteins		
Clone	NCBI gi Accession No.	BLAST pLog Score
cc3.pk0007.g3	2765817	>254
cr1n.pk0154.a3	2765817	51.40
cs1.pk0071.e3	2765817	22.70
cco1.pk0052.b10	2252632	117.00
cta1.pk0005.c1 +	2459447	177.00

TABLE 4-continued

BLAST Results for Clones Encoding Polypeptides Homologous to Mlo Proteins		
Clone	NCBI gi Accession No.	BLAST pLog Score
5' RACE product		
mlo3b3	2459447	111.00
cen3n.pk0062.b7 +	1877221	168.00
5' RACE product		

The sequence of the entire cDNA insert in clone cc3.pk0007.g3 was determined and is shown in SEQ ID NO:1; the deduced amino acid sequence of this cDNA is shown in SEQ ID NO:2. The amino acid sequence set forth in SEQ ID NO:2 was evaluated by BLASTP, yielding a pLog value >254 versus the AtMlo-hl protein sequence. The sequence of a portion of the cDNA insert from clone cr1n.pk0154.a3 is shown in SEQ ID NO:3; the deduced amino acid sequence of this cDNA is shown in SEQ ID NO:4. The sequence of a portion of the cDNA insert from clone cs1.pk0071.e3 is shown in SEQ ID NO:5; the deduced amino acid sequence of this cDNA is shown in SEQ ID NO:6. The sequence of the entire cDNA insert in clone cc1.pk0052.b10 was determined and is shown in SEQ ID NO:7; the deduced amino acid sequence of this cDNA is shown in SEQ ID NO:8. The amino acid sequence set forth in SEQ ID NO:8 was evaluated by BLASTP, yielding a pLog value of 97.10 versus the barley Mlo protein isolog from *Arabidopsis thaliana*. The sequence of the contig assembled with the entire cDNA insert in clone cta1.pk0005.c1 and the 5' RACE product obtained using PCR primer P3 is shown in SEQ ID NO:9; the deduced amino acid sequence of this cDNA is shown in SEQ ID NO:10. The amino acid sequence set forth in SEQ ID NO:10 was evaluated by BLASTP, yielding a pLog value of 157.00 versus the putative Mlo protein from *Arabidopsis thaliana*. The sequence of mlo3b3, the 3' RACE product of cta1.pk0005.c1 obtained using PCR primer P1, is shown in SEQ ID NO:11; the deduced amino acid sequence of this cDNA is shown in SEQ ID NO:12. The sequence of the contig assembled of the cDNA insert from clone cen3n.pk0062.b7 and the 5' RACE product obtained using primer P4 is shown in SEQ ID NO:13; the deduced amino acid sequence of the cDNA is shown in SEQ ID NO:14. Comparison of the 3'-end sequences indicated that clones cs1.pk0071.e3 and cc3.pk0007.g3 are essentially identical at their 3'-untranslated sequences, except for a difference in the polyadenylation site (102 nt insertion), suggesting that these sequences are derived from the same gene. Clones cen3n.pk0062.b7 and cta1.pk0005.c1 differ from each other and from clones cs1.pk0071.e3 and cc3.pk0007.g3 in their 3'-untranslated regions, suggesting that they may be derived from different genes. Clone mlo3b3 has a different 3' end from its parent (cta1.pk0005.c1) suggesting the presence of at least two very similar genes.

The deduced protein sequences were aligned with the NCBI database sequences with the highest pLog and percent similarities were obtained. The data in Table 5 represents a calculation of the percent identity of the amino acid sequences set forth in SEQ ID NOS:2,4,8,10,12 and 14 and the Mlo (or Mlo homolog) sequences present in NCBI.

TABLE 5

Percent Identity of Amino Acid Sequences Deduced From the Nucleotide Sequences of cDNA Clones Encoding Polypeptides Homologous to Mlo Proteins			
Clone	SEQ ID NO.	gi Accession No.	Percent Identity
cc3.pk0007.g3	2	2765817	66.4
cr1n.pk0154.a3	4	2765817	65.4
cc1.pk0052.b10	8	2252632	55.4
cta1.pk0005.c1 +	10	2459447	59.2
5' RACE product			
mlo3b3	12	2459447	60.9
cen3n.pk0062.b7 +	14	1877221	73.7
5' RACE product			

Sequence alignments and percent identity calculations were performed using the Megalign program of the LASAR GENE bioinformatics computing suite (DNASTAR Inc., Madison, Wis.). Sequence percent identity calculations were performed by the Jotun Hein method (Hein, J. J. (1990) Meth. Enz. 183:626-645) using the default settings. For multiple alignments gap penalty=11, gap length penalty=3; for pairwise alignments ktuple=2.

Sequence alignments and BLAST scores and probabilities indicate that the instant nucleic acid fragments encode portions, nearly entire, or entire SCLB^R proteins.

Example 4

Characterization of Corn Genomic Fragments Homologous to cDNA clone cta1.pk0005.c1

A pair of PCR primers, P1 and P2, were designed based on the nucleotide sequence of clone cta1.pk0005.c1.

P1 5'-CAGGTTCACCCACGAGACTT-3' (SEQ ID NO:15)

P2 5'-TTGATGAGGAAAGAGCACGA-3' (SEQ ID NO:16)

Genomic DNA was extracted from 12 distinct corn genotypes, including CM37 and T232, and amplified via PCR using primers P1 and P2. Two amplification products were obtained from amplification of CM37 DNA, one of 765 bp in length, and the other of 703 bp in length. In contrast, amplification of T232 genomic DNA yielded a single amplification product of 703 bp in length. Nucleotide sequence analysis of the 765 and 703 bp PCR products (SEQ ID NOS:15 and 16, respectively) revealed a high degree of homology to the nucleotide sequence of the cDNA insert in clone cta1.pk0005.c1. However, sequence analysis revealed that the 703 bp PCR product comprised two introns while the 765 bp product comprised three introns. The nucleotide sequence of the 703 bp PCR product corresponds exactly to the sequence of cta1.pk0005.c1 cDNA, except for the introns (see FIG. 2). Likewise, the sequence of the 765 bp product is 95% homologous to the cta1.pk0005.c1 insert sequence (again, except for the introns).

Using a 3' RACE amplification system, a cDNA (mlo3b3) was obtained from cta1.pk0005.c1. The nucleotide sequence of mlo3b3 is identical to the 765 bp PCR product without introns (see FIG. 3). Therefore, all three amplification products are related to each other and also to the cta1.pk0005.c1 cDNA insert sequence, and correspond to two corn Mlo-like genes.

Example 5

Genetic Mapping of a Corn Homolog of Barley Mlo

The 765 bp PCR fragment which is produced only from amplification of CM37 genomic DNA and not from T232

genomic DNA is polymorphic between these two genotypes and can therefore be used to map its corresponding gene by analysis of PCR amplification products in a mapping population (48 individuals) resulting from a cross between CM37 and T232. Data was scored on a set of recombinant inbred lines of corn (developed by Dr. Benjamin Burr; see Burr, B. and Burr, F. A. (1991) Trends in Genetics 7:55-60 and Burr, B. et al. (1988) Genetics 118:519-526) from a cross of T232 X CM37. The results of this mapping experiment are shown in Table 6.

¹A designates CM37-like genotype.

²B designates T232-like genotype.

³Genotypes are listed according to the following order of recombinant inbred lines: 2, 4, 6, 7, 9, 11, 12, 13, 14, 15, 16, 17, 18, 19, 20, 21, 22, 23, 24, 25, 26, 28, 29, 31, 32, 33, 34, 35, 36, 37, 38, 39, 40, 41, 42, 43, 44, 45, 46, 47, 48, 49, 51, 53, 54, 55, 56, 57

The data from this experiment were analyzed using the software program Mapmaker 2.0 for Macintosh (adapted from Mapmaker 2.0 for Unix; Lander et al. (1987) *Genomics* 1:174-181) in conjunction with segregation data obtained from Dr. Benjamin Burr for a collection of DNA markers scored in that population. The map scores from the public data set were used by Dr. B. Burr to derive map positions and genetic bin assignment, all of which are available in the Maize Genome Database (<http://www.agron.missouri.edu>). The data presented in Table 6 represents scoring of the RFLP mapping data, except in the case of *cta1.pk0005.c1*, where the data represents the scoring of the PCR product. The RFLP or PCR pattern was examined and compared to the patterns generated from the parents of the genetic cross which produced the mapping population (i.e., T232 and CM37). If the pattern produced resembled that of CM37, it was designated "A". If the pattern produced resembled that of T232, it was designated "B". If the pattern produced resembled that of both CM37 and T232, it was a heterozygote and thus designated "H". "m" denotes missing data. Mapmaker, when used as described in the instructions accompanying the software, produces a genetic map, which is shown in FIG. 1. This map reveals where the *Mlo* cDNA clone *cta1.pk0005.c1* is positioned with reference to other markers.

The genomic segment corresponding to the 765 bp amplification product was mapped to chromosome 6, in Bin 6.01, defined by markers BNL7.28 and UMC59. Three disease resistance loci map to the same bin on chromosome 6: maize dwarf mosaic virus (MDMV), wheat streak mosaic virus (WSMV) and southern corn leaf blight (SCLB). Of the three disease resistance loci, the SCLB locus is unique in that it is the only known recessive disease resistance locus in corn. Therefore, it is highly likely that the corn *Mlo* homolog represented by the 765 bp amplification product (containing

three introns) corresponds to the southern corn leaf blight resistance gene.

Example 6

Expression of Chimeric Genes in Monocot Cells

A chimeric gene comprising a cDNA encoding a SCLB^R protein in sense orientation with respect to the maize 27 kD zein promoter that is located 5' to the cDNA fragment, and the 10 kD zein 3' end that is located 3' to the cDNA fragment,

can be constructed. The cDNA fragment of this gene may be generated by polymerase chain reaction (PCR) of the cDNA clone using appropriate oligonucleotide primers. Cloning sites (NcoI or SmaI) can be incorporated into the oligonucleotides to provide proper orientation of the DNA fragment when inserted into the digested vector pML 103 as described below. Amplification is then performed in a standard PCR. The amplified DNA is then digested with restriction enzymes NcoI and SmaI and fractionated on an agarose gel. The appropriate band can be isolated from the gel and combined with a 4.9 kb NcoI-SmaI fragment of the plasmid pML 103. Plasmid pML 103 has been deposited under the terms of the Budapest Treaty at ATCC (American Type Culture Collection, 10801 University Blvd., Manassas, Va. 20110-2209), and bears accession number ATCC 97366. The DNA segment from pML 103 contains a 1.05 kb Sall-NcoI promoter fragment of the maize 27 kD zein gene and a 0.96 kb SmaI-Sall fragment from the 3' end of the maize 10 kD zein gene in the vector pGem9Zf(+) (Promega). Vector and insert DNA can be ligated at 15° C. overnight, essentially as described (Maniatis). The ligated DNA may then be used to transform *E. coli* XL1-Blue (Epicurian Coli XL-1 Blue^{TM}; Stratagene). Bacterial transformants can be screened by restriction enzyme digestion of plasmid DNA and limited nucleotide sequence analysis using the dideoxy chain termination method (Sequenase^{TM} DNA Sequencing Kit; U.S. Biochemical). The resulting plasmid construct would comprise a chimeric gene encoding, in the 5' to 3' direction, the maize 27 kD zein promoter, a cDNA fragment encoding a SCLB^R protein, and the 10 kD zein 3' region.

The chimeric gene described above can then be introduced into corn cells by the following procedure. Immature corn embryos can be dissected from developing caryopses derived from crosses of the inbred corn lines H99 and

LH132. The embryos are isolated 10 to 11 days after pollination when they are 1.0 to 1.5 mm long. The embryos are then placed with the axis-side facing down and in contact with agarose-solidified N6 medium (Chu et al., (1975) Sci. Sin. Peking 18:659-668). The embryos are kept in the dark at 27° C. Friable embryogenic callus consisting of undifferentiated masses of cells with somatic proembryoids and embryoids borne on suspensor structures proliferates from the scutellum of these immature embryos. The embryogenic callus isolated from the primary explant can be cultured on N6 medium and sub-cultured on this medium every 2 to 3 weeks.

The plasmid, p35S/Ac (obtained from Dr. Peter Eckes, Hoechst Ag, Frankfurt, Germany) may be used in transformation experiments in order to provide for a selectable marker. This plasmid contains the Pat gene (see European Patent Publication 0 242 236) which encodes phosphinothrin acetyl transferase (PAT). The enzyme PAT confers resistance to herbicidal glutamine synthetase inhibitors such as phosphinothrin. The pat gene in p35S/Ac is under the control of the 35S promoter from Cauliflower Mosaic Virus (Odell et al. (1985) Nature 313:810-812) and 3' region of the nopaline synthase gene from the T-DNA of the Ti plasmid of *Agrobacterium tumefaciens*.

The particle bombardment method (Klein et al., (1987) Nature 327:70-73) may be used to transfer genes to the callus culture cells. According to this method, gold particles (1 μ m in diameter) are coated with DNA using the following technique. Ten μ g of plasmid DNAs are added to 50 μ L of a suspension of gold particles (60 mg per mL). Calcium chloride (50 μ L of a 2.5 M solution) and spermidine free base (20 μ L of a 1.0 M solution) are added to the particles. The suspension is vortexed during the addition of these solutions. After 10 minutes, the tubes are briefly centrifuged (5 sec at 15,000 rpm) and the supernatant removed. The particles are resuspended in 200 μ L of absolute ethanol, centrifuged again and the supernatant removed. The ethanol rinse is performed again and the particles resuspended in a final volume of 30 μ L of ethanol. An aliquot (5 μ L) of the DNA-coated gold particles can be placed in the center of a Kapton™ flying disc (Bio-Rad Labs). The particles are then accelerated into the corn tissue with a Biolistic™ PDS-1000/He (Bio-Rad Instruments, Hercules Calif.), using a helium pressure of 1000 psi, a gap distance of 0.5 cm and a flying distance of 1.0 cm.

For bombardment, the embryogenic tissue is placed on filter paper over agarose-solidified N6 medium. The tissue is arranged as a thin lawn and covered a circular area of about 5 cm in diameter. The petri dish containing the tissue can be placed in the chamber of the PDS-1000/He approximately 8 cm from the stopping screen. The air in the chamber is then evacuated to a vacuum of 28 inches of Hg. The macrocarrier is accelerated with a helium shock wave using a rupture membrane that burst when the He pressure in the shock tube reaches 1000 psi.

Seven days after bombardment the tissue can be transferred to N6 medium that contains glufosinate (2 mg per liter) and lacks casein or proline. The tissue continues to grow slowly on this medium. After an additional 2 weeks the tissue can be transferred to fresh N6 medium containing glufosinate. After 6 weeks, areas of about 1 cm in diameter of active growing callus can be identified on some of the plates containing the glufosinate-supplemented medium. These calli may continue to grow when sub-cultured on the selective medium.

Plants can be regenerated from the transgenic callus by first transferring clusters of tissue to N6 medium supple-

mented with 0.2 mg per liter of 2,4-D. After two weeks the tissue can be transferred to regeneration medium (Fromm et al., (1990) Bio/Technology 8:833-839).

5 Example 7

Expression of Chimeric Genes in Dicot Cells

A seed-specific expression cassette composed of the promoter and transcription terminator from the gene encoding the P subunit of the seed storage protein phaseolin from the bean *Phaseolus vulgaris* (Doyle et al. (1986) J. Biol. Chem. 261:9228-9238) can be used for expression of the instant SCLB^R proteins in transformed soybean. The phaseolin cassette includes about 500 nucleotides upstream (5') from the translation initiation codon and about 1650 nucleotides downstream (3') from the translation stop codon of phaseolin. Between the 5' and 3' regions are the unique restriction endonuclease sites Nco I (which includes the ATG translation initiation codon), Sma I, Kpn I and Xba I. The entire cassette is flanked by Hind III sites.

The cDNA fragment of this gene may be generated by polymerase chain reaction (PCR) of the cDNA clone using appropriate oligonucleotide primers. Cloning sites can be incorporated into the oligonucleotides to provide proper orientation of the DNA fragment when inserted into the expression vector. Amplification is then performed as described above, and the isolated fragment is inserted into a pUC 18 vector carrying the seed expression cassette.

Soybean embryos may then be transformed with the expression vector comprising sequences encoding SCLB^R proteins. To induce somatic embryos, cotyledons, 3-5 mm in length dissected from surface sterilized, immature seeds of the soybean cultivar A2872, can be cultured in the light or dark at 26° C. on an appropriate agar medium for 6-10 weeks. Somatic embryos which produce secondary embryos are then excised and placed into a suitable liquid medium. After repeated selection for clusters of somatic embryos which multiplied as early, globular staged embryos, the suspensions are maintained as described below.

30 Soybean embryogenic suspension cultures can maintained in 35 mL liquid media on a rotary shaker, 150 rpm, at 26° C. with florescent lights on a 16:8 hour day/night schedule. Cultures are subcultured every two weeks by inoculating approximately 35 mg of tissue into 35 mL of liquid medium.

35 Soybean embryogenic suspension cultures may then be transformed by the method of particle gun bombardment (Kline et al. (1987) Nature (London) 327:70, U.S. Pat. No. 4,945,050). A Du Pont Biolistic™ PDS1000/HE instrument (helium retrofit) can be used for these transformations.

40 A selectable marker gene which can be used to facilitate soybean transformation is a chimeric gene composed of the 35S promoter from cauliflower mosaic virus (Odell et al. (1985) Nature 313:810-812), the hygromycin phosphotransferase gene from plasmid pJR225 (from E. coli; Gritz et al. (1983) Gene 25:179-188) and the 3' region of the nopaline synthase gene from the T-DNA of the Ti plasmid of *Agrobacterium tumefaciens*. The seed expression cassette comprising the phaseolin 5' region, the fragment encoding the SCLB^R protein and the phaseolin 3' region can be isolated as a restriction fragment. This fragment can then be inserted into a unique restriction site of the vector carrying the marker gene. To 50 μ L of a 60 mg/mL 1 μ m gold particle suspension is added (in order): 5 μ L DNA (1 μ g/ μ L), 20 μ L spermidine (0.1 M), and 50 μ L CaCl₂ (2.5 M). The particle preparation is then agitated for three minutes, spun in a

microfuge for 10 seconds and the supernatant removed. The DNA-coated particles are then washed once in 400 μ L 70% ethanol and resuspended in 40 μ L of anhydrous ethanol. The DNA/particle suspension can be sonicated three times for one second each. Five μ L of the DNA-coated gold particles are then loaded on each macro carrier disk. Approximately 300–400 mg of a two-week-old suspension culture is placed in an empty 60 $\times$ 15 mm petri dish and the residual liquid removed from the tissue with a pipette. For each transformation experiment, approximately 5–10 plates of tissue are normally bombarded. Membrane rupture pressure is set at 1100 psi and the chamber is evacuated to a vacuum of 28 inches mercury. The tissue is placed approximately 3.5 inches away from the retaining screen and bombarded three times. Following bombardment, the tissue can be divided in half and placed back into liquid and cultured as described above.

Five to seven days post bombardment, the liquid media may be exchanged with fresh media, and eleven to twelve days post bombardment with fresh media containing 50 mg/mL hygromycin. This selective media can be refreshed weekly. Seven to eight weeks post bombardment, green, transformed tissue may be observed growing from untransformed, necrotic embryogenic clusters. Isolated green tissue is removed and inoculated into individual flasks to generate new, clonally propagated, transformed embryogenic suspension cultures. Each new line may be treated as an independent transformation event. These suspensions can then be subcultured and maintained as clusters of immature embryos or regenerated into whole plants by maturation and germinations of individual somatic embryos.

Example 8

Expression of Chimeric Genes in Microbial Cells

The cDNAs encoding the instant corn SCLB^R proteins can be inserted into the T7 E. coli expression vector pBT430. This vector is a derivative of pET-3a (Rosenberg et al. (1987) Gene 56:125–135) which employs the bacteriophage T7 RNA polymerase/T7 promoter system. Plasmid pBT430 was constructed by first destroying the EcoR I and Hind III sites in pET-3a at their original positions. An oligonucleotide adaptor containing EcoR I and Hind III sites was inserted at the BamH I site of pET-3a. This created pET-3aM with additional unique cloning sites for insertion of genes into the expression vector. Then, the Nde I site at

the position of translation initiation was converted to an Nco I site using Oligonucleotide-directed mutagenesis. The DNA sequence of pET-3aM in this region, 5'-CATATGG, was converted to 5'-CCCATGG in pBT430.

Plasmid DNA containing a cDNA may be appropriately digested to release a nucleic acid fragment encoding the protein. This fragment may then be purified on a 1% NuSieve GTG™ low melting agarose gel (FMC). Buffer and a(garose contain 10 μ g/ml ethidium bromide for visualization of the DNA fragment. The fragment can then be purified from the agarose gel by digestion with GELase™ (Epicentre Technologies) according to the manufacturer's instructions, ethanol precipitated, dried and resuspended in 20 μ L of water. Appropriate oligonucleotide adapters may be ligated to the fragment using T4 DNA ligase (New England Biolabs, Beverly, Mass.). The fragment containing the ligated adapters can be purified from the excess adapters using low melting agarose as described above. The vector pBT430 is digested, dephosphorylated with alkaline phosphatase (NEB) and deproteinized with phenol/chloroform as described above. The prepared vector pBT430 and fragment can then be ligated at 16° C. for 15 hours followed by transformation into DH5 electrocompetent cells (GIBCO BRL). Transformants can be selected on agar plates containing LB media and 100 μ g/mL ampicillin. Transformants containing the gene encoding the SCLB^R protein are then screened for the correct orientation with respect to the T7 promoter by restriction enzyme analysis.

For high level expression, a plasmid clone with the cDNA insert in the correct orientation relative to the T7 promoter can be transformed into E. coli strain BL21 (DE3) (Studier et al. (1986) J. Mol. Biol. 189:113–130). Cultures are grown in LB medium containing ampicillin (100 mg/L) at 25° C. At an optical density at 600 nm of approximately 1, IPTG (isopropylthio- β -galactoside, the inducer) can be added to a final concentration of 0.4 mM and incubation can be continued for 3 h at 25° C. Cells are then harvested by centrifugation and re-suspended in 50 μ L of 50 mM Tris-HCl at pH 8.0 containing 0.1 mM DTT and 0.2 mM phenyl methylsulfonyl fluoride. A small amount of 1 mm glass beads can be added and the mixture sonicated 3 times for about 5 seconds each time with a microprobe sonicator. The mixture is centrifuged and the protein concentration of the supernatant determined. One μ g of protein from the soluble fraction of the culture can be separated by SDS-polyacrylamide gel electrophoresis. Gels can be observed for protein bands migrating at the expected molecular weight.

What is claimed is:

1. An isolated polynucleotide comprising:

(a) a nucleic acid sequence a polypeptide selected from the group consisting of SEQ ID NO:2, SEQ ID NO:4, SEQ ID NO:6, SEQ ID NO:8, SEQ ID NO:10, SEQ ID NO:12 and SEQ ID NO:14; [and] or

(b) a nucleic acid sequence that is complementary to (a).

2. A chimeric nucleic acid sequence comprising the isolated polynucleotide of claim 1 operably linked to at least one suitable regulatory sequence.

3. A transformed host cell comprising the chimeric nucleic acid sequence of claim 2.

4. A method of [altering] *reducing* the expression level of Mlo polypeptide in a host cell, the method comprising:

(a) transforming a host cell with the chimeric nucleic acid sequence of claim 2; and

(b) growing the transformed host cell of step (a) under conditions suitable for expression of the chimeric nucleic acid sequence;

wherein expression of the chimeric nucleic acid sequence results in production of [altered] *reduced* Mlo polypeptide levels in the transformed host cell *increasing disease resistance*.

5. A method of obtaining an isolated polynucleotide encoding an Mlo polypeptide comprising:

(a) probing a cDNA or genomic library with at least 30 contiguous nucleotides of the isolated polynucleotide of claim 1; and

(b) isolating the cDNA clone or genomic DNA clone identified in step (a);

6. A method of obtaining an isolated polynucleotide encoding an Mlo polypeptide, the method comprising:

(a) synthesizing an oligonucleotide primer corresponding to at least 30 contiguous nucleotides of the isolated polynucleotide set forth in any of SEQ D NOS:1, 3, 5, 7, 9, 11, 13, 18 and 19; and

(b) amplifying a cDNA insert present in a cloning vector using the oligonucleotide primer of step (a)

wherein the amplified isolated polynucleotide encodes an Mlo polypeptide.

7. The product of the method of claim 5.

8. The product of the method of claim 6.

9. An expression cassette comprising an isolated polynucleotide of claim 1 operably linked to a promoter.

10. An isolated polynucleotide comprising:

(a) a first nucleic acid sequence that is at least 80% identical by the Jotun Hein method of alignment to a nucleic acid molecule encoding a polypeptide set forth in SEQ ID NO:2, SEQ ID NO:4, SEQ ID NO:6, SEQ ID NO:8, SEQ ID NO:10, SEQ ID NO:12, or SEQ ID NO:14; or

(b) a second nucleic acid sequence that is complementary to the first isolated polynucleotide.]

[11. A chimeric nucleic acid sequence comprising the isolated polynucleotide of claim 10 operably linked to at least one suitable regulatory sequence.]

[12. A transformed host cell comprising the chimeric nucleic acid sequence of claim 11.]

[13. A method of altering the expression level of Mlo polypeptide in a host cell, comprising:

(a) transforming a host cell with the chimeric nucleic acid sequence of claim 11; and

(b) growing the transformed host cell of step (a) under conditions that are suitable for expression of the chimeric nucleic acid sequence, wherein expression of the chimeric nucleic acid sequence results in altered Mlo polypeptide levels in the transformed host cell.]

14. A method for producing a transgenic plant, comprising:

(a) transforming a plant cell with an expression cassette of claim 9; and

(b) regenerating the transformed plant cell of (a) to produce a transgenic plant.

15. An isolated polynucleotide as set forth in SEQ ID NOS:1, 3, 5, 7, 9, 11, or 13.
